UNITED STATES PATENT OFFICE.

STEPHEN JARVIS ADAMS, OF PITTSBURG, PENNSYLVANIA.

METHOD OF AND APPARATUS FOR MAKING SAND MOLDS.

SPECIFICATION forming part of Letters Patent No. 586,751, dated July 20, 1897.

Application filed August 4, 1890. Serial No. 360,891. (No model.)

To all whom it may concern:

Be it known that I, STEPHEN JARVIS ADAMS, a resident of Pittsburgh, in the county of Allegheny and State of Pennsylvania, have invented a new and useful Improvement in Methods of and Apparatus for Making Sand Molds; and I do hereby declare the following to be a full, clear, and exact description thereof.

10 My invention relates to the making of sand cores and molds, its object being to pack the cores or molds by compression in such way as to obtain evenly-packed cores and molds in forming deep cores or molds, such as those 15 employed in forming wagon-boxes, pipe-balls, and like tubular articles.

The particular improvements included in the invention will be hereinafter set forth and claimed.

20 To enable others skilled in the art to make and use my invention, I will describe the same more fully, referring to the accompanying drawings, in which—

Figure 1 is a vertical section of apparatus 25 suitable for practicing the same, part of the apparatus being shown in side view. Fig. 2 is a cross-section on the line 2 2, Fig. 1. Fig. 3 is a detail longitudinal section, partly in full lines, showing the operation of the apparatus 30 in the downward stroke of the packer. Fig. 4 is a detail view showing the packing of the upper end of the core and showing the insertion of the core-rod into the core. Figs. 5 and 6 are detail plan views, partly in section, 35 showing other forms of reservoir. Fig. 7 illustrates a modification of the measuring apparatus, and Fig. 8 is a view showing my invention as applied to the packing of molds.

Like letters and numerals of reference indicate like parts in each.

In the apparatus illustrated in the drawings I have shown several forms illustrative of the main invention, and the principal description will be given of the form as illustrated in Fig. 1, though it will be understood that the apparatus there shown is simply illustrative of the general principle, equivalent devices for the same purpose being included within my invention.

50 The frame A is of any suitable construction, and it has about midway thereof a table a, on which the movable measuring-box b

and the sand-reservoir B are supported, while below the table a is a cross-frame a', in which the lower end of the core-box or flask c is 55 supported, said frame a' generally having a guiding-seat a² to direct the base of the core-box to the proper position. In the table a is also formed a seat a³ for the upper end of the core-box or flask, this seat or guideway, in 60 connection with the lower seat or guideway a², holding the flask or core-box in proper line with the packing apparatus. Resting on said table a is a plate a⁵, which is preferably 65 formed of hardened and polished steel, as its face is subjected to considerable wear, this plate extending under the movable measuring-box b and the plate having an opening in it over the seat a³ of the table corresponding to the opening in the core-box or flask, the 70 plate a⁵ resting on the upper edge of the core-box or flask and acting to hold it in place.

The movable measuring-box b can be formed of wood or metal, being preferably formed of sheet metal and made vertically 75 adjustable, as hereinafter described and as illustrated in Fig. 4, so as to provide deeper or shallower measuring-pockets for the measuring of the sand, as may be found desirable. In said measuring-box are a series of measuring-holes b', which are adapted to come over the opening in the core-box or flask and feed the sand to the same. In Figs. 1 and 2 this measuring-box is shown as a circular box mounted on a central axis, as at b³, and the 80 several measuring-pockets are equally distant from the center of the box, so that they may be drawn over the seat a³ of the table and over the top of the core-box or flask. These pockets b² may either be all of the same diameter or may be made of different diameters, as shown in Fig. 2, according to the relative diameter of the core-box or pattern at the point to which the sand is to be fed therein.

95 The sand-reservoir B rests upon the movable measuring-box or such box passes within the base of the sand-reservoir, as may be desired, and the sand-reservoir corresponds substantially in shape to the measuring-box, except at the point where the core-box or flask is supported in the apparatus, at which point one of the openings b² of the measuring-box is exposed, as shown in Fig. 2, the sand-res-

ervoir having a V or like shaped partition B', exposing such opening, so that upon the turning of the plate the sand entering the pockets of the measuring-box will be drawn out 5 of the reservoir and in line with the core-box, so that the sand may pass down into the core-box, the pressing-packer passing down through such opening b² of the measuring-box. As the pockets of the measuring-box 10 thus pass within the reservoir the plate a⁵ forms the bases of the pockets, which are filled with sand from the reservoir and are struck off even by the edge of the partition B', so carrying out a regulated quantity of sand. 15

Suitable apparatus is provided for feeding sand to the reservoir, which it is not considered necessary to illustrate.

The movable measuring-box can be operated either automatically or by hand, and, if desired, the table a may be mounted at the rear end on bearings a⁴ in the frame, so that it, with the reservoir and measuring-box supported thereon, may be lifted slightly in securing the core-box or flask in place. 20

The vertically-movable packer d is secured at the base of the shaft D, which passes through suitable bearings D' D² in the frame A, and said packer d is mounted centrally of 25 the core-box, so that in its packing-stroke it will pass centrally into the core-box and force down and spread the sand fed thereto on each side thereof. The packer is not of as great diameter as the internal diameter of the core-box, and its lower part d is preferably made tapering, as shown, so that the principal action will be to spread the sand and force it outwardly against the walls of the core-box. 30 The upper part of the packer d, as at d², is also preferably formed tapering in the opposite direction, so that it may shed any sand passing onto this part of the packer. 35

Any suitable means for imparting a stroke to the packer may be employed, such as by 40 foot-power or by a small engine or other suitable mechanism. As, however, it is desirable to regulate the pressure according to the depth to which the sand is packed within the reservoir I have provided mechanism suitable for 45 this purpose and which can be employed in a regular automatically-operating machine. For this purpose I employ a cam E, mounted on a shaft e, and I provide the shaft D with the frame f, the outer edges of the cam being 50 arranged to come in contact with a pin or roller e' for lifting the packer or permitting the same to drop, while mechanism for forcing down the packer is provided in connection with the frame f and side or face of the cam. 55 In the frame f I place a pin or roller g, which is out of line with the edge of the cam, but extends out sufficiently to engage with wings on the face of the cam, these wings being numbered 1, 2, 3, 4, 5, &c., and being arranged 60 eccentric to the movement of the cam and in such position that upon the rotation thereof they will engage with the pin or roller g and

force the shaft D and its packer d downwardly. This is more clearly shown in detail view Fig. 3. The operation of this part of the apparatus is therefore such that when the shaft d is permitted to descend by the movement of the roller e' over the face e² of the cam E until it is supported by the sand in the core-box upon the further movement of the cam the roller g 70

will engage with one of the wings on the cam-face, which, on account of the eccentric position thereof, will force down the packer, so as to impart a packing-pressure to the sand. Instead of the series of wings on the presser 80 I may employ the equivalent thereof, a series of pins on the frame and a single eccentrically-placed wing on the cam to engage with one of the pins according to the position of the packer. After the core-box has been 85 packed in this way up to the top thereof in order to level the top of the core off and to impart a sufficient pressure over the whole top face of the core to compact the head thereof I prefer to employ a block, as shown at h in 90 Fig. 4, which fits within the upper end of the core-box and through the measuring-pocket b² of the measuring-plate b, said block having a conical seat on its upper face into which the packer d may fit, said packer thus forcing the 95 block h down into the core.

In order to provide a core-rod to handle the core, I provide for the insertion of said rod after the formation of the core, and for this purpose I employ a guideway I centrally below the core-box, said guideway extending between the frame a' and a like frame I', supported in the main frame A. Below the guideway I is a bar k, the upper end of which fits in the guideway I, while its lower end passes 105 through a bearing in the cross-bar k' of the frame A, said bar k having a pin k² with which a lever k³ engages, so that the bar k may be forced upwardly through the guideway I. 110

Prior to the formation of the core a core-rod i is inserted in the guideway I, and when the packing of the core is finished the operator through the lever k³ and bar k forces the core-rod i upwardly into and through the core within the core-box c, as shown in Fig. 4. 115 The block h may, if desired, have a recess h², into which the upper end of the core-rod i may enter, this core-rod therefore providing means for the withdrawal of the core from the core-box and its insertion within the mold. 120

In practicing my invention with the apparatus above described the core-rod i is first inserted in the guideway I. The core-box c is then placed in position in the guideways a² a³, the plate a⁵ resting on the upper edge 125 thereof. The operator then draws one of the measuring-pockets b² of the measuring-box b, such as the smaller pocket thereof, over the core-box, when the sand, which has been measured in the manner above described, will drop 130 into the core-box, filling the lower end thereof. Upon the rotation of the cam E the bar D will descend, and its roller e' travels on the face e² of the cam until the packer d rests upon

and is supported by the sand, and upon the further rotation of the cam E the roller g on the frame f will engage with one of the eccentric flanges on the cam-face, such as the flange 5 7, (the lowest one on the face of the cam,) which on account of its eccentricity will force the packer downwardly, and the conical base d' of the packer d will spread out the sand, packing it downwardly and sidewise against 10 the walls of the core-box. Upon the further rotation of the cam E the packer will be raised above the measuring-box b and the measuring-box can again be moved, so as to bring the next measuring-pocket over the core-box 15 and permit the sand to pass down into the same, and the packer will again descend within the core-box until it rests on the loose sand therein, and its roller will be engaged by the next flange 6 on the cam E, the pack- 20 ing pressure being again applied and the sand being spread outwardly against the walls of the core-box. This is continued until the entire core-box is packed, the sand being alternately measured and fed thereto and spread 25 and packed therein and, if desired, a greater body of sand being fed thereto, according to the increased diameter and depth of the core-box. As soon as the core is packed up to the upper end thereof the last measuring-pocket 30 is brought over the same, feeding a large quantity of sand thereto, and in order to compact the upper end of the core the operator then inserts the block h, corresponding in shape to the flask or core-box and having a 35 flat pressing-face, and through the packer d forces said block downwardly, so as to apply the packing pressure over the entire top face of the core. While this block is thus held in place the operator raises the bar k and it 40 forces the core-rod i upwardly through the core, its upper end entering the hollow seat h² in the block h, so that when said block is removed the core-rod can be grasped by the operator, and after the core is loosened from 45 the core-box the core may be withdrawn by said core-rod and inserted in the drying-frame or placed directly in the mold.

If desired, suitable connections can be made with the measuring-box, so that these operations can be automatic, though such connections form no part of the present invention.

As it may be desirable to increase or decrease the amount of sand fed at each movement of the measuring-box I sometimes make 55 the box adjustable, as shown in Fig. 4, forming the pockets b² thereof telescopic, each pocket being formed of two tubes or cylinders l l', the one fitting within the other, the tubes l being secured to the top plate l², while 60 the tubes l' are secured to the bottom plate l³. In order to adjust such plates toward or from each other and so decrease or increase the length of the measuring-pockets, any suitable mechanism may be employed, that shown in 65 the drawings being interiorly-threaded tubes l⁴, secured to the top plate, and bolts l⁵, swiv- elled to the bottom plate and screwing into

the tubes l⁴, so as to adjust the distance between the top and bottom plates, as may be desired.

In Figs. 5, 6, and 7 I have illustrated different forms of reservoirs and measuring-boxes, the reservoir M in Fig. 5 being formed on both sides of the opening through which the sand is fed to the core-box and the measuring-box m being mounted on the table a and having two pockets, the one pocket passing under one wing m' of the reservoir when the other pocket is drawn out from the reservoir and over the opening to the core-box, 70 and the plate having an oscillating movement, so that when the pocket passing under the wing m' is drawn out over the core-box the other pocket will pass under the wing m² to receive a supply of sand from that part of 75 the reservoir.

In Fig. 6 I have illustrated the apparatus where a series or row of cores is to be formed at one time, such apparatus being adapted for the making of small cores, and in that 80 case the measuring-box n has simply a single row of measuring-pockets n', which when drawn out coincide with the openings of the core-boxes, and to receive a fresh supply of sand are pushed back under the sand-reser- 85 voir N, the measuring-pocket reciprocating 90 in suitable guideways and being passed first under the stationary reservoir m⁴ and receiving the sand and then drawn out to feed it through the pockets n' to the core-boxes un- 95 der the same.

In Fig. 7 I have illustrated another form of reservoir and measuring-box, the measuring-box p in this case being mounted on a horizontal axis p' and having a series of wings 100 p², between which are spaces p³, forming the measuring-pockets. This wheel is mounted at the base of the reservoir P, the lower part of which corresponds to the outer circumference of the measuring-box and from which a 105 chute P' extends down to the opening to the core-box. In such case as the measuring-box is turned the sand passes down the chute into the core-box and is packed by the rammer, 110 and the proper amount of sand fed to the core- 115 box, according to the different points at which the packing operation is carried on; can be varied by changing the sizes of the pockets upon the circular box, different-sized spaces p³ being arranged upon the box p, as may be 120 desired.

In Fig. 8 I have illustrated the way of packing molds according to my invention, the mold illustrated being one in which there is a central space r' for forming the core within the 125 pattern r and a space s between the pattern r and the flask, and to pack such a flask I employ a packer substantially such as illustrated in the drawings, having either tapering sides or a flat base, the central packer t for packing 130 within the space r being substantially such as above described, while the packer T for packing the space s between the pattern r and the flask is an annular packer adapted to enter

the annular space around the pattern and act upon the sand about centrally of such space, so as to compact or spread the sand against the flask and against the pattern. In such 5 apparatus the sand is fed at intervals to the flask in substantially the manner above described, and the packer is forced down upon the sand and withdrawn until a further feeding of sand takes place, this being continued 10 until the entire flask is filled. The particular improvements in connection with forming these molds by my invention forms the subject-matter of a separate application of even date herewith, Serial No. 360,890, and does 15 not require any further detailed description.

In any of the forms in which my invention is practiced it is evident that I am enabled to form deep cores or molds by pressing and to pack the sand evenly as it is fed to the core-box or mold only in such quantity as can be 20 properly and evenly compacted by the pressing-tool at that particular pressing operation, and I may employ a number of regulated feeds of just the right quantity of sand that can be 25 compacted evenly by the strokes of the packer, and may employ a series of light pressures instead of feeding a large body of sand and attempting to compact it at one time by a heavy pressure. At the same time as each successive 30 body of sand fed to the core-box is compacted and pressed to its proper place, and that is followed up by a further body of sand again forced to its proper place, a deep core or mold can be evenly packed by a compressing operation, this not having been found practicable heretofore. As I also provide for the 35 spreading of the sand through the conical or tapering packer, I am enabled to force the sand against the walls of the core-box, flask, 40 or pattern and obtain the packing thereof outwardly and so obtain the proper packing of the sand even though there are variations in the shape of the core-box or pattern. The 45 operation can either be practiced by hand or the apparatus arranged to work automatically, and it provides an efficient method of forming such sand cores or molds.

What I claim as my invention, and desire to secure by Letters Patent, is—

- 50 1. The herein-described method of forming cores and molds, consisting in feeding the sand to the box or flask, dropping the packer down onto the same until it rests on and is supported by the sand and then forcing down 55 the packer to pack the sand, substantially as and for the purposes set forth.
2. In apparatus for forming molds, the combination of the frame carrying guideways for receiving the core-box or flask, and a table 60 mounted on pivots at the rear end of said frame and extending forward and having a guiding-seat at the forward end thereof for

the reception of the upper end of the core-box or flask, substantially as and for the purposes set forth. 65

3. In apparatus for forming cores or molds, the combination of a core-box or flask, a vertically-reciprocating packer carried on a bar and entering the same, and a cam constructed to engage said bar at different heights and 70 force the packer against the sand within the flask, substantially as and for the purposes set forth.

4. In apparatus for forming sand molds, the combination of a core-box *c* supported in a 75 suitable seat, the guideway *I* for the reception of the loose core-rod *i*, the vertically-moving bar *k* separate from the core-rod and adapted to enter said guideway and to be withdrawn from the guideway sufficiently to 80 enable a core-rod to be placed in position below the core and mechanism for moving the bar *k* longitudinally, substantially as set forth.

5. In apparatus for forming sand molds, the 85 combination of the guide-seats *a²a³*, the core-box *c* supported therein, the guideway *I* for the reception of the core-rod *i*, vertically-moving bar *k* adapted to enter said guideway, and a lever *k³* engaging with said bar *k*, 90 substantially as and for the purposes set forth.

6. In apparatus for forming molds, the combination of the core-box, the removable block *h*, having the recess *h²*, a guide below the core-box, a loose core-rod in said guide and a pusher below the same for forcing the core-rod through the core and into the recess *h²* of the removable block, substantially as and for the 95 purposes set forth. 100

7. In apparatus for forming molds, the combination with a core-box or flask, of a packer secured to a vertically-reciprocating bar *D*, having a frame *f* provided with a pin *g*, and a rotating cam or like device having a series 10 of eccentric wings on the face thereof at different distances from its center, to engage with the upper face of said pin, substantially as and for the purposes set forth.

8. In apparatus for forming molds, the combination with a core-box or flask of a packer secured to a vertically-reciprocating bar *D* having a frame *f* and provided with pins *e'* and *g*, and a rotating cam engaging with the pin *e'* and having one or more eccentric wings 11 on the face thereof to engage with the upper face of the pin *g*, substantially as and for the purposes set forth. 110

In testimony whereof I, the said STEPHEN JARVIS ADAMS, have hereunto set my hand. 12
STEPHEN JARVIS ADAMS.
